(57) **CLAIM**

The ornamental design for motor drive enclosure, as shown and described.

DESCRIPTION

This application is related to co-pending U.S. Design Patent application Serial No. 29/331,633, entitled "Motor Drive Enclosure," filed on Jan. 29, 2009, which is hereby incorporated by reference in its entirety.

FIG. 1 is a front perspective view of the motor drive enclosure;

FIG. 2 is a front view of the motor drive enclosure of FIG. 1; FIG. 3 is a rear view of the motor drive enclosure of FIG. 1; FIG. 4 is a top view of the motor drive enclosure of FIG. 1; FIG. 5 is a bottom view of the motor drive enclosure of FIG. 1;

FIG. 6 is a left side view of the motor drive enclosure of FIG. 1; and,

FIG. 7 is a right view of the motor drive enclosure of FIG. 1. The broken lines in the drawings are for illustrative purposes only, and do not form part of the claimed design.
